UNITED STATES PATENT OFFICE.

EUGENE F. HEDRICK, OF FORT BAYARD, TERRITORY OF NEW MEXICO.

TRIGGER MECHANISM.

No. 906,419.

Specification of Letters Patent.

Patented Dec. 8, 1908.

Application filed May 27, 1908. Serial No. 435,251.

To all whom it may concern:

Be it known that I, EUGENE F. HEDRICK, a citizen of the United States, and a resident of Fort Bayard, in the county of Grant and Territory of New Mexico, have invented certain new and useful Improvements in Trigger Mechanism, of which the following is a specification.

My invention is an improvement in trigger mechanism, and consists in certain novel constructions and combinations of parts herein-after described and claimed.

Referring to the drawings forming a part hereof. Figure 1 is a central longitudinal section through a gun provided with the trigger mechanism, with the hammer not set, and showing the mechanism arranged for plain trigger. Fig. 2 is a similar view showing the hammer set. Fig. 3 is a similar view showing the hammer not set, and the trigger mechanism arranged as a set trigger. Fig. 4 is a similar view, showing the hammer set. Fig. 5 is a similar view showing the setting of the hammer by the action of the guard lever. Fig. 6 is an enlarged detail section of the trigger mechanism proper, and Fig. 7 is a top plan view of the same.

In the present embodiment of my invention, the hammer 1 is pivoted as at 2 in the frame, and is provided with a forwardly projecting lug 3, engaged by one end of a powerful plate spring 4, whose other end is connected to the barrel by a screw 5. The rear face of the hammer is provided with a curved surface 6, having at approximately the center thereof, a notch 7, which is adapted for engagement by a lug 8 on the lower sear 9 to be presently described, and the breech block 10 is pivoted on the pivot 2 of the hammer. The lower sear 9 is provided with a cam surface 11 for engagement by the rounded surface 6 of the hammer, and the lug 8 before mentioned, is arranged at the upper end of the cam surface. The lower sear is provided with an upwardly extending lug 12, which is received between ears 13, on the upper sear 14, and the end of the upper sear adjacent to said pivotal connection is pivoted on a pin 14^a, arranged transversely of the frame. The rear end of the upper sear has pivoted thereto the trigger arm 15, and the said arm is provided on its front face with an under-cut notch 16, which is adapted for engagement by a hook 17 on the lower sear, when the parts are in the plain trigger position shown in Figs. 1 and 2. A change screw 18 is

threaded through the lower sear, the free end thereof engaging the upper sear, whereby to press the hook 17 into engagement with the notch 16 to lock the parts in the plain trigger position. A spring 29 is provided with an eye 30, through which passes a pin 31 on the upper sear, and one end 32 of the spring engages the frame, the other end 33 engaging the trigger arm, as shown at 36 for a purpose to be presently described.

It will be evident from the description, that when it is desired to use the trigger mechanism in plain trigger position, the change screw is loosened until the hook 17 can be engaged with the notch 16, after which the change screw is tightened to lock the parts in this position. To arrange the mechanism in set trigger position, the change screw is loosened until the hook 17 can be disengaged from the notch 16, after which the change screw is turned home to its limit. This brings the edge of the notch 16 into position for engagement by a lug 35 on the lower sear, as shown in Fig. 6, and a set screw 36 is threaded through the lower sear, in a diagonal direction as shown in Fig. 1 to 6 inclusive, the free end of the set screw being adapted to limit the engagement of the edge of the notch with the lug.

When the hammer is set either by hand or by the lever 14, with the trigger mechanism in the plain trigger position, the notch 7 of the hammer is engaged by a lug 37 on the upper sear, as shown in Fig. 2, but when the mechanism is in the set trigger position, the notch is engaged by the lug 8, as before mentioned. In either case the operation of setting the hammer swings the rear end of the trigger mechanism upward through the engagement of the curved surface 6, with the curved surface 11, and the spring 29 acts to return the trigger mechanism into position, such that either the lug 8 or the lug 37 will engage the notch 7 of the hammer. The plate spring 4 acts not only to operate the hammer, but also to return the lever 40 to its closed position. The rounded portion 6 of the hammer acting on the cam surface 11 of the lower sear, serves to move the lug 8 away from the notch 7, and also to permit the lug 35 on the upper sear to engage said notch when the mechanism is in the set trigger position. When the trigger is pulled, the parts being in the position shown in Fig. 6, the lug 35 on the lower sear is released from the edge of the under cut notch 16, and the

action of the hammer spring tends to move said hammer forward. This movement forces the pivotal connection of the sears backwardly away from the hammer, and the 5 engagement of the curved surface 6 of the hammer with the lower end 11 of the sear, forces the projection 8 of the sear out of the engagement with the notch 7 of the hammer. When the parts are in the position shown in 10 Figs. 1 and 2, the bodily movement of the trigger, positively releases the lug 37 of the upper sear from the notch 7 of the hammer.

It will be obvious from the description, that by loosening the change screw, and engaging the shoulder 17 with the notch, 16, and afterwards tightening the change screw, the mechanism will act as a plain trigger, the upper sear engaging the hammer when the gun is cocked, and a considerable pull will be 20 necessary to release the hammer.

By placing the change screw in the position shown in Figs. 3, 4 and 6, the edge of the notch 16 will engage with the lug 35, and the extent of the engagement may be varied by 25 the set screw 36, so that a moderately heavy or extremely light pull on the trigger will release the hammer. When in this position the lower sear engages the hammer.

It will be observed that all of the parts are 30 actuated by the plate spring 4, the small spring 29 being for the purpose only of returning the trigger mechanism to its original position when moved backwardly and upwardly by the curved portion of the hammer.

35 I claim:

1. The combination with the hammer having a curved rear face and an upwardly facing notch, of a pivotally mounted upper sear having a lug for engaging the notch, a lower 40 sear pivoted to the upper sear, and having a cam surface for engagement by the curved surface of the hammer, and a lug for engaging the said notch, a trigger arm pivoted to the free end of the upper sear, and provided 45 with an undercut notch, the lower sear being provided with a hook for engaging the notch, when the trigger mechanism is in plain trigger position, and with a shoulder for engaging the edge of the notch when the trigger is in set trigger position, a set screw for limiting the extent of engagement of the sear with the 50 edge of the notch, and a change screw threaded through the lower sear and engaging the upper sear, for locking the hook in engagement with the notch, or for spacing the lower sear from the upper sear for the purpose set forth.

2. The combination with a hammer having a curved rear face, and a notch, of a pivotally mounted upper sear having a lug for engaging the notch, a lower sear pivoted to the upper sear and having a cam surface for engagement by the curved surface of the hammer, and a lug for engaging the notch, a 60 trigger arm pivoted to the free end of the

upper sear, and provided with a notch, the lower sear being provided with a hook for engaging the last named notch, and a shoulder for engaging the edge of the notch, means for limiting the extent of engagement of the shoulder with the edge of the notch, and a change screw threaded through the lower sear, and engaging the upper sear for locking the hook in engagement with the notch, or for spacing the lower sear from the upper 75 sear for the purpose set forth.

3. The combination with the hammer having a curved rear face and an upwardly facing notch, of a pivotally mounted upper sear for engaging the notch, a lower sear pivoted 80 to the upper sear, and having a cam surface for engagement by the curved surface of the hammer, and a lug for engaging the notch, a trigger arm pivoted to the free end of the upper sear, and provided with an undercut 85 notch, the lower sear being provided with a hook for engaging the notch, and with a shoulder for engaging the edge of the notch, means for limiting the extent of engagement of the shoulder with the edge of the notch, 90 and means for locking the hook in engagement with the notch, or for spacing the lower sear from the upper sear for the purpose set forth.

4. In trigger mechanism, a pivotally mounted upper sear, a lower sear pivoted to the upper sear, a trigger arm pivoted to the free end of the upper sear, and provided with an under-cut notch, the lower sear being provided with a hook for engaging the notch, 95 when the trigger mechanism is in plain trigger position, and with a shoulder for engaging the edge of the notch when the trigger is in set trigger position, a set screw for limiting the extent of engagement of the sear with the 100 edge of the notch, and a change screw threaded through the lower sear and engaging the upper sear, for locking the hook in engagement with the notch, or for spacing the lower sear.

5. In trigger mechanism, an upper sear pivoted at one end, a lower sear pivoted to the upper sear, a trigger arm pivoted to the free end of the upper sear, and provided with an under-cut notch, the lower sear being provided with a hook for engaging the notch, 115 when the trigger mechanism is in plain trigger position, and with a shoulder for engaging the edge of the notch when the trigger is in set trigger position, means for limiting the extent of engagement of the shoulder with the edge of the notch, and means for locking the hook in engagement with the notch, or for spacing the lower sear from the upper sear for the purpose set forth.

6. In trigger mechanism, an upper sear, a lower sear pivoted thereto a trigger arm pivoted to the upper sear, means for locking the sears and the trigger arm in fixed relation with respect to each other, the lower sear be- 120

ing provided with a shoulder, and the trigger arm with a notch for engagement by the shoulder when in set trigger position, and means for limiting the extent of engagement 5 of the shoulder and the notch.

7. A trigger mechanism comprising a pivotally mounted upper sear, a lower sear pivoted to the upper sear, and normally in position for engagement by the hammer, a trigger arm pivoted to the upper sear and having 10 a limited engagement with the lower sear whereby to retain the hammer in set position, and means for locking the sears and the trigger arm together whereby to move the 15 lower sear out of engaging position.

8. A trigger mechanism comprising a pivotally mounted upper sear, a lower sear pivoted to the upper sear, and normally in position for engagement by the hammer, a trigger arm pivoted to the upper sear and having 20 a limited engagement with the lower sear whereby to retain the hammer in set position, and means for locking the sears and the trigger arm together whereby to move the 25 lower sear out of engaging position, and means for varying the extent of the engagement of the trigger arm and the lower sear.

9. A trigger mechanism comprising an upper sear adapted to engage the hammer, and 30 pivoted by the end adjacent to the hammer, a lower sear for engaging the hammer pivoted to the upper sear, said lower sear being normally in position for engaging the hammer, a trigger arm pivoted to the free end of 35 the upper sear, and having a limited engagement with the lower sear to prevent swinging movement thereof, means for varying the extent of engagement, and means for locking

the sears and the trigger arm together whereby to move the lower sear out of engaging 40 position.

10. In trigger mechanism, the combination with the pivotally connected sears, of a trigger arm pivoted to the upper sear, and having a limited engagement with the lower 45 sear for preventing swinging movement thereof with respect to the upper sear, means for varying the extent of engagement, and means for locking the sears and the trigger arm together for the purpose set forth. 50

11. In trigger mechanism, the combination with the pivotally connected sears, of a trigger arm pivoted to the upper sear, and having a limited engagement with the lower 55 sear for preventing swinging movement thereof, with respect to the upper sear, and means for locking the sears and the trigger arm together, for the purpose set forth.

12. In trigger mechanism, the combination with the pivotally connected sears, of a trigger arm pivotally connected to the upper sear, means in connection with the trigger and the lower sear, whereby said trigger and sear may have a limited engagement with each other, and means for locking the sears 65 and the trigger arm together.

13. In trigger mechanism, pivotally mounted sears, a trigger arm pivoted to one sear, and having a limited engagement with the other, and means for locking the sears 70 and the trigger arm together.
